ABRASIVE POLISHING DEVICE

Aleck Block, Culver City, Calif.

Application October 10, 1955, Serial No. 539,623

11 Claims. (Cl. 51—194)

This invention relates to an abrasive polishing device and more particularly to a circular abrasive band and means for rotatably mounting the same.

It is an object of my invention to provide an abrasive device for light grinding and polishing purposes which utilizes a circular abrasive band which is simply and economically manufactured of discardable materials. It is particularly an object of my invention to provide such a band which comprises a replaceable unit which may be quickly and easily removed and replaced with a fresh unit when it has become worn. Toward this end, it is a further object of my invention to provide a mounting means for such a band which permits and provides simple and rapid replacement of the abrasive band.

Another object of my invention is to provide an abrasive band of the type described in which fresh abrasive material becomes available for use as the old abrasive material is used and worn away, thus extending the life of the band and providing improved and substantially uniform abrasive action throughout the extended life of the band.

In essence, my invention contemplates providing an abrasive band which is formed around a central circular core member, which preferably comprises a flat ring of substantially rigid but economical material such as cardboard tubing or the like. Mounted around the entire outer surface of the ring are short strips of cloth or paper which are coated with suitable abrasive material on the outer sides thereof. The abrasive strips extend axially with respect to the core member and are adhered thereto. The abrasive strips are disposed in a continuously overlapping relationship so that as the edge of each strip becomes worn away, it exposes the fresh abrasive material on the strip disposed therebeneath. The band is sufficiently rigid to permit it to be easily handled and replaced as a unit. It may be discarded when worn out without loss of valuable parts or materials.

My abrasive band is adapted to be mounted on a rotatable mandrel which includes a cylindrical core formed of resilient material. The outer diameter of the core is substantially equal in size to the inner diameter of the band. The ends of the core are compressed to cause the diameter of the core to expand and engage the inner surface of the band. The ends of all of the abrasive coated strips extend into the interior of the band, where they engage the core and are tightly held between the core of the mandrel and the core member of the band.

My invention also comprises such other objects, advantages and capabilities as will later more fully appear and which are inherently possessed by my invention.

While I have shown in the accompanying drawings a preferred embodiment of my invention, it should be understood that the same is susceptible of modification and change without departing from the spirit of my invention.

Referring to the drawings, Fig. 1 is a side elevational view of my abrasive band in use;

Fig. 2 is a side elevational view of the same taken from the opposite side;

2

Fig. 3 is a front elevational view of the same;

Fig. 4 is a sectional view of the same taken on line 4—4 of Fig. 1;

Fig. 5 is a perspective view of my abrasive band.

5 A preferred embodiment which has been selected to illustrate my invention comprises an abrasive band 10, which is formed around a central circular core member 11, which preferably comprises a flat ring of substantially rigid but economical material such as a piece of cardboard tubing or the like. The width of the core member 11 may be varied in accordance with the size of the material being polished.

15 A plurality of small substantially rectangular abrasive strips 12 are adhered to the outer surface of core member 11. The abrasive strips 12 extend axially with respect to core member 11 around its entire circumference. The abrasive strips 12 are preferably cut from cloth or paper which is coated with suitable abrasive material on one side thereof, the other side being plain. The plain side of each of the strips 12 is adhered to the outside of the core member 11 and to the adjacent abrasive strip with a suitable adhesive such as vinyl glue or the like. The strips 12 are arranged so that each strip overlaps the adjacent strip a substantial amount, the amount of overlapping preferably being approximately one-half the width of the strip.

20 It should be noted that a sufficient number of strips 12 should be provided so that the exposed portion of each strip is substantially small in area. If the exposed area is too large, the abrasive material will wear off the outside of the strip, leaving smooth paper or cloth exposed. If the exposed area is smaller, the edge of each of the strips 12 strikes the material being polished and the strip wears away, with the wear extending inwardly from the 25 edge to expose fresh abrasive material therebeneath. With a large number of strips, the total area thus worn away is considerably greater than if a small number of strips were used.

30 The opposite ends of each of the strips 12 extend into the interior of the core member 11 and are adhered thereto. The ends preferably extend a substantial distance inwardly from the edge of the core member 11 for reasons hereinafter set forth.

35 In use, my abrasive band 10 is mounted on a mandrel 45 13, which comprises an elongated shaft 14 having an integral wedge 15 at one end thereof. The other end of shaft 14 is adapted to be attached to a suitable source of rotation. The shaft 14 extends through centrally disposed openings in an inner end plate 16, a cylindrical core 17 and an outer end plate 18. The outer end plate 18 is provided with a concave portion which receives the wedge 15 of shaft 14. The portion of shaft 14 adjacent inner end plate 16 is screw threaded to receive a nut 19. As the nut 19 is tightened, the end plates 16 and 18 are forced together, exerting pressure on the ends of the core 17. 50 The core 17 is formed of resilient material such as rubber or the like, so that it expands when nut 19 is tightened.

55 The outer diameter of the core 17 is preferably normally slightly smaller than the inner diameter of the abrasive band 10. The band 10 is mounted on the core 17 and nut 19 tightened to expand the diameter of core 17. As this occurs, the core 17 exerts pressure against the ends of each of the strips 12, pressing them tightly against the core member 11 to prevent the strips from 60 coming loose during rotation of the band.

65 This action is important to the operation of my invention, since the adhesive alone is ordinarily insufficient to hold the strips 12 on the core member 11. The pressure of the core 17 reinforces the adhesive and prevents the ends of the strips 12 from being pulled loose from the core member 11 during the high speed rotation necessary to use the band for grinding and polishing purposes.

The abrasive material on the ends of the strips 12 within the interior of the core member 11 further provides added frictional grip between the ends of the strips 12 and the core 17.

I claim:

1. An abrasive band comprising a central circular core member formed of a substantially rigid piece of cardboard tubing, a plurality of small rectangular abrasive strips adhered to the outer surface of said core member around the entire circumference thereof, said strips extending axially with respect to said core member, each of said strips having abrasive material on the exposed side thereof, said strips being disposed in substantially overlapping relationship to each other, the opposite ends of each of said strips extending a substantial distance into and being adhered to the interior of said core member, there being a sufficient number of said strips so that each strip has an exposed edge adapted to wear away in use to expose the portion of the adjacent strip disposed therebeneath.

2. The subject matter of claim 1, and rotatable mounting means for said band including a shaft, a cylindrical core axially mounted on said shaft, said core being formed of resilient material, a pair of side plates mounted adjacent the opposite ends of said core, the normal outer diameter of said core being slightly smaller than the inner diameter of said abrasive band, said band adapted to be removably mounted on said core, and means for moving said side plates together to expand the diameter of said core, said core engaging the ends of each of said strips to hold said strips firmly against said core member to prevent their separation from said core member during rotation of said band.

3. The subject matter of claim 2, the portions of the ends of said abrasive strips disposed within the interior of said core member having abrasive material thereon, said abrasive material adapted to engage said core to provide a friction grip between said core and the ends of said leaves.

4. An abrasive band comprising a substantially rigid central circular core member, a plurality of abrasive strips adhered to the outer surface of said core member around the entire circumference thereof, said strips extending axially with respect to said core member, each of said strips having abrasive material on the exposed side thereof, said strips being disposed in overlapping relationship to each other, the opposite ends of each of said strips extending into and being adhered to the interior of said core member.

5. The subject matter of claim 4 and means for mounting said abrasive band for high speed rotation, said mounting means including a core disposed within said core member, said core being expandable to grip the ends of said strips, the ends of said strips being firmly held between

said core and core member to prevent the separation of said strips from said core member during rotation of said band.

6. The subject matter of claim 5, the ends of said strips having abrasive material thereon, said abrasive material providing a friction grip between said strips and said core.

7. An abrasive band comprising a substantially rigid circular core member, a plurality of abrasive strips adhered to the outer surface of said core member around the entire circumference thereof, said strips extending axially with respect to said core member, each of said strips having abrasive material on the outer side thereof, the opposite ends of each of said strips extending into and being adhered to the interior of said core member.

8. The subject matter of claim 7 and means for mounting said abrasive band for high speed rotation, said mounting means including a core disposed within said core member, said core being expandable to grip the ends of said strips, the ends of said strips being firmly held between said core and core member to prevent the separation of said strips from said core member during rotation of said band.

9. An abrasive band comprising a substantially circular core member, a plurality of abrasive strips mounted on the outer surface of said core member around the entire circumference thereof, said strips extending axially with respect to said core member, each of said strips having abrasive material on the exposed surface thereof, the opposite ends of each of said strips extending into the interior of said core member.

10. The subject matter of claim 9 and means for mounting said abrasive band for high speed rotation, said mounting means including a core disposed within said core member, said core being expandable to grip the ends of said strips, the ends of said strips being firmly held between said core and core member to prevent the separation of said strips from said core member during rotation of said band.

11. The subject matter of claim 9, said strips substantially overlapping each other around the entire circumference of said core member.
